UNITED STATES PATENT OFFICE

WILLIAM F. FALLS, OF BOSTON, MASSACHUSETTS, ASSIGNOR OF ONE-HALF
TO FRANK GREENWOOD, OF HYDE PARK, MASSACHUSETTS.

DESIGN FOR A LADY'S WORK-STAND.

SPECIFICATION forming part of Design No. 30,009, dated January 17, 1899.

Application filed December 12, 1898. Serial No. 698,083. Term of patent 14 years.

To all whom it may concern:

Be it known that I, WILLIAM F. FALLS, a citizen of the United States, residing at Boston, in the county of Suffolk and State of Massachusetts, have invented and produced a new and useful Design for a Lady's Work-Stand, of which the following is a full, clear, and exact description.

Referring to the drawing forming part of this specification, the figure is a perspective view of the work-stand embodying my new design.

The essential feature of my design comprises the vertical post or rod rising from a base and having a series of disks or holders carried thereby at various points thereof.

The reference character 2 indicates the post or rod, rising from the base 1. At about one-third of the height of the post 2 is the basket or receptacle 3, said post passing through the axial center of said receptacle. At about two-thirds of the height of the post 2 is a disk 4, having projecting vertically from

its upper surface the pins 5, the post passing through the center of said disk. At the upper extremity of the post 2 is a rounded head 8, formed of fabric and stuffed to retain its shape. About midway between said disk 4 and head 8 is a second disk 6, somewhat smaller than the former and having rounded 30 projections 7 upon its upper surface.

Made in accordance with this design a lady's work-stand is given a light and dainty effect and is an attractive and salable article.

Having described my invention, what I claim as new, and desire to secure by Letters Patent, is—

The design for a lady's work-stand, as herein shown and described.

In testimony that I claim the foregoing invention I have hereunto set my hand this 30th day of November, 1898.

WILLIAM F. FALLS.

Witnesses:

FRANK F. FALLS,
A. B. UPHAM.
